UNITED STATES PATENT OFFICE.

JOSEPH HIRST, OF NEW LONDON, CONNECTICUT.

GAS-ENGINE.

SPECIFICATION forming part of Letters Patent No. 714,799, dated December 2, 1902.

Application filed October 19, 1901. Serial No. 79,266. (No model.)

To all whom it may concern:

Be it known that I, JOSEPH HIRST, a citizen of the United States, residing at New London, in the county of New London and State of Connecticut, have invented certain new and useful Improvements in Gas-Engines, of which the following is a full, clear, and exact description.

The chief object of this invention is to provide extremely cheap and effective mechanism for use in gasoline and the like engines, whereby the force of successive explosions in a multiple of cylinders may be transmitted to the constantly-revolving shaft, the novel arrangement of said mechanism being such that space is economized and power conserved.

My said improvement is specially valuable for use in connection with marine engines, but may also be used with advantage in stationary engines.

In order to explain my said improvement most clearly, I have annexed hereto a sheet of drawings illustrating those portions of a "four-cycle" engine that relate to and embody my present improvements.

Figure 1 is an elevation of that portion of a gasoline-engine in which the pistons are located, showing also in proper relation thereto the driven shaft and my improved means for transmitting motion from the pistons to the said shaft. In this figure a considerable portion of the casing within which the pistons operate is broken away to show the interior parts. Fig. 2 is a cross-sectional view 35 of the same parts, taken on line 2 2 of Fig. 1.

Inasmuch as my improvements relate only to the arrangement of the power-cylinders and pistons with relation to the driven shaft and to the means for transmitting motion and power from said pistons to said shaft I have thought it unnecessary to illustrate other portions of the engine.

In the accompanying drawings the letter *a* denotes a water-jacketed casing in which the cylinders *a'* and pistons *b* are located, and it should be particularly noted that the pistons are arranged in a line that is transverse to the axial center of the driven shaft. Said shaft is designated by the reference-letter *c* and is journaled in suitable bearings in a housing or shell *d*. (Shown in dotted lines

in the drawings.) Mounted on shaft *c* within the said housing is a gear *c'*, and upon the exposed end of the shaft is a hand-wheel *c''*. Within the housing *d* are also pinion-gears *e*, 55 here shown as four in number, that mesh with the gear *c'* and are mounted on studs *e'*, that are journaled in bosses formed on the said housing.

In axial alinement with the studs *e'* are shafts *g*, also journaled in the housing and having secured to their inner ends crank-disks *h*, each disk being connected with the confronting pinion *e* by a crank-pin *h'*, as is best seen in Fig. 2. The pinions *e*, as already 65 stated, are in mesh with the gear *c'*, and they are so disposed with relation to the pistons that they may be connected with said pistons by connecting-rods *b'*. The pistons of a four-cycle engine embodying the described mechanism may be set to operate in pairs, as here illustrated, or they may be set at "quarters," 70 so as to operate upon the driven shaft in succession, thus overcoming dead-centers.

One of the advantages which the described 75 arrangement of pistons and crank mechanism has over the commonly-used engines in which the pistons are arranged in a line parallel with the driven shaft and connected directly thereto by cranks is in the obvious 80 economy of space, particularly when used as a marine engine.

Heretofore this class of engines have been arranged with the pistons and power-cylinders running "fore and aft" of the boat; but 85 my new arrangement of driving mechanism, as described, arranges said pistons and cylinders transversely to the length of the screw-shaft, and thus renders it possible and practicable to shorten said shaft somewhat and 90 to locate the engine nearer the screw, thus increasing correspondingly the open space or seating capacity of the boat.

Having thus described my invention, I claim—

In a gas-engine, the combination of a driven shaft, a water-jacketed casing, parallel cylinders therein, pistons in said cylinders and all disposed in a line transverse to the axial center of said shaft, a housing, a gear on said shaft within the housing, a wheel on the extended end of the shaft, gears within the

housing all meshing with the gear on the shaft and all disposed above the horizontal axial center of the shaft and mounted on studs journaled in bosses on said housing, 5 shafts in axial line with said studs and also journaled in said housing, crank-disks on the ends of said shafts, a crank-pin on each disk, connecting each disk to the confronting gear, and a rod connecting each piston with a crank-

pin and disposed between the crank-disk and 10 gear, all substantially as shown and described.

Signed at New London, Connecticut, this 7th day of October, 1901.

JOSEPH HIRST.
